UNITED STATES PATENT OFFICE.

CLAUDE L. CONGDON, OF HOMER, NEW YORK.

SMOKING-PIPE ACCESSORY.

Application filed March 10, 1926. Serial No. 93,665.

My invention relates to removable smoking pipe devices and more particularly to an appliance serving as a grate-like member adapted to be inserted into the bowl portion of such pipes to keep its tubular mouth piece free from clogging and obviate the waste of unburned tobacco.

One object of my invention is to provide a smoking pipe with a removable bowl grate adapted to trap any ash, juice or other waste matter, and prevent such by-products from working their way up into the bit of the pipe stem. The combustible matter such as tobacco, is intended to be burned above the grate, and the grid thereof is preferably fashioned into a circular plate provided with relatively numerous perforations affording a free smoke and also a well distributed draft through the pipe bowl.

20 A further object of the present invention is to provide for improved means for suitably mounting the grate into the pipe bowl. To this end, my appliance is preferably equipped with a pendant abutment member to 25 fixedly locate the grate means irrespective of the bowl depth and without resort to support straps hanging from the edge of the bowl mouth. My spacing means may be formed in the shape of a rigid stop member 30 protruding from the grid, which plate is held in spaced relation with respect to the bottom of the bowl and forms a trap pocket below the grate. The opening through the pipe stem communicates with this trap 35 chamber, which is adapted to collect any fluid or solid waste particles and prevents them from being sucked up into the mouth piece of the pipe.

The rim of such a grid plate may further 40 be provided with resilient bowl gripping means that serve to hold the grate down in position and allows a single size of grate plate to be fitted to a range of different bowl bores. Embodied herein are also suitable 45 means designed to permit of easy removal of the grate for pipe cleaning purposes, and other features of structure adapted to facilitate the manufacture and application of said device to smoking pipes, all of which will 50 be set forth in further detail hereinafter.

Reference is had to the accompanying one sheet drawing which illustrates a specific embodiment of my invention; like characters of reference indicate like parts through-

out the several views, and in which drawing:

Fig. 1 illustrates an elevational view taken in partial section of a conventional tobacco pipe showing my improved baffle device placed within the pipe bowl.

Fig. 2 is a top view of Fig. 1.

Fig. 3 shows a triangular sheet metal blank from which my device may be formed up.

Fig. 4 represents a top view of said blank 65 as completely formed up and ready to be inserted into a suitable pipe bowl.

Fig. 5 is a sectional view of the completed device as taken along line 5—5 of Fig. 4.

Fig. 6 shows a bottom view of Fig. 5.

Fig. 7 shows a modified form of my grate device.

Referring first to Fig. 1, the letter 1 designates a pipe bowl provided with a lateral stem portion 2 wherein is formed the smoke duct serving to connect the tubular mouth piece 4 with the bottom portion 1^a of said bowl. The bowl side walls 1^b are usually shaped in substantially cylindrical fashion and extend up to its mouth 1^c.

The manner in which my device is intended to be installed within the bowl is clearly indicated in Fig. 1. If desired, my grate device may comprise an upstanding reinforcing rim portion 5 and a stop base or 85 abutment portion 6 having an intermediate grid portion 7. An integral grate structure of this kind may be conveniently stamped out of sheet metal into a triangular blank having a shape such as indicated by Fig. 3, 90 where the centrally disposed base portion 6 is shown as drawn out of such flat stock.

The circular portion of the blank may initially be provided with a plurality of radially disposed bowl gripping prongs 8 95 and these are subsequently formed up as shown in Fig. 5, the prong ends being preferably kinked and sprung outwardly so as to extend beyond the diameter of the completed rim 5. The sheet metal used for making up my device is preferably of a resilient character such as will enable the prongs to firmly press against the interior bowl wall 1^b and properly hold the grate down in its lowermost position. Most pipe bowls are 105 made to conform to a few standard sizes and the corresponding periphery of my grid need only fit reasonably close therein, and if

desired a small gap 1^D may be allowed for between the surrounding side wall 1^B as indicated so as to more readily fit into different bowl shapes.

5 The dished grid portion 7 of my device is provided with a series of spaced draft apertures 9 adapted to impart a screen effect and establish communication between a trap pocket 10^A and a tobacco bowl space 10^B lying above the grate. To facilitate removal of the grate, the edge of the rim 5 may be provided with an inturned peripheral ledge or spaced claws designated as 11. Such ledge portions may readily be engaged 15 by suitable tool as for instance a headed nail, hook or the like, to forcibly withdraw the grate from the bowl, but it is pointed out that the use of said claws is not an essential feature of my device.

20 Fig. 7 shows a modified type of abutment in that the rigid depending distance piece 6^{A'} is here fashioned into a separate pin centrally adjoined to the grate which also answers intended purposes. It will be apparent therefor that the appended abutment 6 need not necessarily be formed in the integral fashion shown in Fig. 4, but that the more essential member of such grate stop lies in its distance piece or spacing element 30 designated as 6^A. This holds the grid 7 in a fixed relation with respect to the bottom of the bowl while the resilient prongs 8 prevent the device from falling out of place and together make for thoroughly practicable attachment that will readily fit into any of the ordinary styles of pipes.

The entrance of the smoke duct 3 into the interior of the bowl is normally placed close to the bottom thereof, and the interconnected trap pocket 10^A not only maintains a free draft through the pipe but also provide ample space for the accumulation of saliva slime, tobacco products, or a mixture thereof which might otherwise be sucked up into 45 the mouth piece 4 or tend to clog the stem. The size of the individual draft holes 9 is preferably made small relative to the cross-sectional area of the smoke duct 3, in order to prevent the finer tobacco particles from falling into the trap chamber, but the aggregate area of said plural draft holes is intended to be considerably larger than the smoke passage 3 to effect an evenly distributed draft through the burning tobacco 55 and to make for a free and clean smoke.

As a result of the use of such a pipe grate, the tobacco may also be packed more closely into the bowl than applies when a localized draft through the pipe charge is obliged to head toward a single side outlet in the usual 60 fashion.

Better economy in the use of tobacco is also attained with my device for the reason that my spaced grid holds the fresh charge off the bowl bottom which in turn prevents the fresh tobacco from becoming impregnated with accumulated waste juices; accordingly the entire body of smoking tobacco may wholly be consumed down to the face of my grid disc without experiencing 70 any distressing effects from smoking unclean tobacco or sucking up its saliva derivatives as is likely to occur in the use of the conventional untrapped smoking pipe. When it is desired to completely clean out 75 the pipe, the described device may readily be removed, whereupon the entire contents of the bowl may be ejected and should it become necessary, the interior thereof conveniently scraped of cake formation.

It is to be understood that it is not my intent to limit the scope of the present invention to specific structure or materials herein disclosed, since the disposition of the parts and especially the described type of 85 stop means 6^A may readily be varied or changed to meet conditions of practice in accordance with the judgment or experience of the manufacturer, all without departing from the spirit and scope of my invention 90 as heretofore described and more particularly set forth in the appended claim.

I claim:

In an accessory for smoking pipes having a bowl portion and a mouth piece, a 95 grate-like device removably mounted within the pipe bowl and comprising a perforated grid means equipped with an upstanding rim portion conforming to the bore contour of the bowl and with a rigid 100 distance piece depending centrally from said grate and adapted to abut the bottom portion of the bowl for grid spacing purposes, and prong means for said rim adapted to give lateral support to the device and prevent tilting thereof about said abutment.

In testimony whereof, I have herewith set my hand this 9th day of March, 1926.

CLAUDE L. CONGDON.
